GRAVE LINING PROTECTION UNIT

Randolph E. Gleason, Paul H. Coffey, and George Reuter, Roanoke, Va.

Application November 13, 1941, Serial No. 418,966

9 Claims. (Cl. 72—7)

Our invention relates to a grave lining protective unit and more particularly to a unit adapted to be disposed in a grave over the coffin and its enclosing case, box or vault to prevent the sinking of the earth fill in the grave when the vault box and coffin collapse through decay, rot or the like.

As is well known, many cemeteries sell or lease the plots therein under a contract which guarantees that the grave will receive perpetual care. We have found that the decay and collapse of the coffin and more particularly its surrounding box is the major cause of the sinking of graves and is one of the major items of cost to the cemetery under such perpetual care guarantees.

With the foregoing in view, an object of our invention is to provide novel means for supporting the earth fill irrespective of the condition of coffin and its surrounding box, and which supporting means will be substantially imperishable.

A further object is to provide such a supporting means which is applicable to the grave after the coffin and box or vault enclosing the same has been placed in the grave without the use of special tools or any particular skill.

A further object is to provide such a device which is of knockdown construction whereby to facilitate its manufacture, storage, transportation and its application to the grave.

A further object is to provide such a device with widely spaced supporting means or legs and a solid top whereby loose earth may pass around and beneath the solid top to pack around the legs and coffin container when the grave is filled and whereby the solid top will prevent further settling or sinking of the earth after the grave has been once filled.

A further object is to provide means to prevent the support or lining itself from sinking into the ground, which means comprise footings for the support thereof and which footings may also include means for facilitating the positioning of the support in the grave.

Other objects and advantages reside in the particular structure of our invention as a whole, the structure of the several parts, combination and arrangement of the latter and in the particular method of protecting a grave against sinking, all of which will be readily apparent to those skilled in the art upon reference to the drawing and specification wherein the invention is shown, described and claimed.

In the drawing:

Fig. 1 is a perspective view of one form of the invention;

Fig. 2 is a plan thereof showing the same in position in a grave;

Fig. 3 is a longitudinal, vertical section taken substantially in the plane of the line 3—3 of Fig. 2;

Fig. 4 is a transverse vertical section taken substantially in the plane of the line 4—4 of Fig. 2;

Fig. 5 is a perspective view of a corner support for the device;

Fig. 6 is a like view of a side support of the same;

Fig. 7 is a perspective view of a footing for the corner supports;

Fig. 8 is a like view of a footing for the side supports.

Referring specifically to the drawing, 10 designates generally our support as a whole which is a table-like member comprising a top 11, corner supports 12 and side supports 13. The top 11 is preferably made in two pieces and may be secured to the side supports 13 in any suitable manner as by the bolts 14 which are imbedded in the upper ends of the side supports 13. The

bolts 14 extend upwardly from the supports 13 and above the uppermost plane of the top 11. Nuts 15 are thereafter applied to the bolts to clamp the top 11 in place. Obviously, there is but little need for the bolts and nuts 14, 15 where

the floor of the grave is substantially level as the weight of the top 11 will suffice to hold it in place until the earth fill is applied. Moreover, it will be noted that the corner legs 12 are angular in plan whereby they stand upright by themselves

and provide a firm support for the top 11. Also, the support conforms so closely to the shape and size of the grave that the flat side supports 13 have no room between the coffin and grave side wall in which to fall over. This feature is clearly indicated in Figs. 3 and 4 wherein the coffin container 25 is shown in broken lines.

Where the ground is unduly soft, it is sometimes necessary to provide footings to prevent the support itself from sinking into the ground.

In such instances, footings 22 and 23 may be provided for the corner and side supports 12 and 13 respectively. The corner footings 22 may be provided with an outer upstanding flange 21 to insure the proper positioning of the corner legs 12 thereon. In like manner, the side footings

23 may each be provided with a longitudinal slot 24 to receive the bottom edge of the corresponding side leg 13, whereby to maintain the latter upright. In practice, where footings are to be used they are pre-formed in the grave floor by

casting or are ready made and applied to the grave floor before the coffin container is lowered therein. However, the support 10 is not applied to the grave until after the coffin and its container have been lowered into the grave and just prior to the initial filling thereof with earth. As is shown, the support has a close fit in the grave and by making the support of knockdown construction its application to the grave is facilitated and the necessity for special tackle and a large crew of men is avoided. Obviously, however, it is possible to make the device in one piece and to lower it into the grave as a unit. By making the device of table-like form much of the loose dirt applied to the grave when it is filled sifts around the top 11 and packs around the legs 12 and 13 as well as the coffin container 25 in the usual manner, whereby to give stability to the legs 12 and 13.

Any suitable material may be used to construct our support as long as the material is capable of supporting a heavy load and is substantially imperishable in use. We do not limit ourselves to any particular material. The drawing shows the device formed of reinforced concrete slabs and angle and we have found that this material is well nigh ideal for our purpose on account of its durability and cheapness.

While we have shown and described what is now thought to be the preferred form of the invention, it is to be understood that the same is susceptible of other forms and expressions. Consequently, we do not limit ourselves to the precise structure shown and described except as hereinafter claimed.

We claim:

1. A device to prevent sunken graves, comprising a plurality of laterally spaced upright legs adapted to straddle a coffin container in a grave and to be supported upon the floor of the grave, and a solid top member supported by said legs and adapted to overlie said container.

2. A device to prevent sunken graves, comprising a plurality of individual legs adapted to be applied in laterally spaced upright positions

on a grave floor between the walls of the grave and a coffin container resting on the grave floor, and a solid top adapted to be supported by gravity upon the upper ends of said legs.

3. The structure of claim 2, there being substantially wide spaces between said legs to permit the packing of earth therearound as said grave is filled.

4. The structure of claim 2, said legs comprising an angular leg for each corner of said grave and a pair of flat legs for the sides of said grave intermediate said corner legs.

5. The structure of claim 2, said legs comprising an angular leg for each corner of the grave, a pair of flat legs for the sides of the grave intermediate the corner legs, and means for securing said top to the upper edges of said side legs.

6. A table-like device for preventing sunken graves, comprising a plurality of spaced and upright legs adapted to rest upon the floor of a grave, a solid top carried by said legs, and individual footings in the floor of said grave supporting said legs, said footings each including guide means to facilitate the proper positioning of said legs in said grave.

7. A device to prevent sunken graves comprising four angle members adapted to be arranged in upright position on the floor of a grave each in a corner of the grave between the coffin container and the side walls of the grave, said members extending above the upper plane of said container, and a substantially solid slab supported upon the upper ends of said members.

8. A table-like device for preventing sunken graves, comprising a plurality of laterally spaced masonry legs adapted to rest upon the floor of a grave, and a solid masonry top carried by said legs on the upper ends thereof.

9. The structure of claim 8, said top comprising a pair of like sections arranged end to end and adapted to be supported upon said legs by gravity.
